CLAIM

The ornamental design for an earphone case, as shown and described.

DESCRIPTION

FIG. 1 is a front perspective view of a first embodiment of an earphone case, showing our new design;

FIG. 2 is a front view thereof;

FIG. 3 is a back view thereof;

FIG. 4 is a top view thereof;

FIG. 5 is a bottom view thereof;

FIG. 6 is a right side view thereof;

FIG. 7 is a left side view thereof;

FIG. 8 is a back perspective view thereof;

FIG. 9 is a front perspective view of a second embodiment of an earphone case, showing our new design;

FIG. 10 is a front view thereof;

FIG. 11 is a back view thereof;

FIG. 12 is a top view thereof;

FIG. 13 is a bottom view thereof;

FIG. 14 is a right side view thereof;

FIG. 15 is a left side view thereof; and,

FIG. 16 is a back perspective view thereof.

The broken lines in drawings show portions of the earphone case that form no part of the claimed design.

1 Claim, 16 Drawing Sheets
